UNITED STATES PATENT OFFICE.

LOUIS T. FREDERICK, OF WILKINSBURG, PENNSYLVANIA, ASSIGNOR TO WESTINGHOUSE ELECTRIC AND MANUFACTURING COMPANY, A CORPORATION OF PENNSYLVANIA.

PROCESS OF MAKING COMPOSITE TUBES.

1,284,298.

Specification of Letters Patent. Patented Nov. 12, 1918.

No Drawing.

Application filed December 18, 1914. Serial No. 877,980.

To all whom it may concern:

Be it known that I, LOUIS T. FREDERICK, a citizen of the United States, and a resident of Wilkinsburg, in the county of Allegheny and State of Pennsylvania, have invented a new and useful Improvement in Processes of Making Composite Tubes, of which the following is a specification.

My invention relates to the manufacture of composite tubes composed of absorbent sheet material treated with an adhesive substance, and it has for its object to provide a simple and effective process for producing composite tubes of the above-indicated character without the use of elaborate apparatus or the exercise of a high degree of skill.

In the electrical insulating art, much use is made of tubes composed of paper or other fibrous material coated or impregnated with an adhesive, which may be a varnish gum such as shellac or a synthetic resin such as the well-known phenolic condensation products. The process heretofore commercially employed for producing such tubes consists in treating paper with the adhesive material and winding the treated paper upon a mandrel with the simultaneous application of heat, tension and pressure, the heat being applied for the purpose of softening the adhesive and the tension and pressure being necessary in order to unite the successive layers into a compact mass. This procedure makes necessary the use of rather complicated apparatus which requires the attention of highly skilled operatives.

According to my present process, I proceed by wrapping upon a mandrel one or two turns of untreated paper, and I then apply to the mandrel a sufficient number of turns of coated fibrous absorbent material to give a tube wall of the required thickness. This fibrous material, which is ordinarily paper, is provided, before being wound on the mandrel, with a dried coating of a phenolic condensation product, shellac or other suitable adhesive, and the treated paper is wrapped around the mandrel as tightly as can be done by hand. The mandrel carrying the treated paper is then placed in a heated mold in which it is pressed and heated for a period of time depending upon the size of the tube. The temperature is then lowered sufficiently to allow the tube and mandrel to be taken from the mold without damaging the tube. If the adhesive material contains

a phenolic condensation product, the temperature need not be lowered, provided that the heat has been applied for a sufficient period to harden the adhesive material. When the tube and mandrel have cooled sufficiently for handling, the mandrel may be withdrawn and any fins caused by the mold then removed.

The process described above produces tubes much more quickly than is possible by the methods heretofore employed, because the hot-wrapping process is necessarily carried out at a slow rate. Furthermore, as has already been pointed out, my process requires less complicated apparatus and less skill on the part of the operatives than the hot-winding process.

While I have described my process with reference to the use of paper and an adhesive material comprising a phenolic condensation product, it is to be understood that any equivalent materials may be substituted for them, as convenience or necessity may require. It is also to be understood that the steps of my process may be variously modified by persons skilled in the art, and that my invention is therefore limited only by the scope of the appended claims.

I claim as my invention:

1. A process of making tubes that comprises treating fibrous material with an adhesive material comprising a phenolic condensation product, winding the treated fibrous material upon a mandrel without heat or pressure, subjecting the wound material to heat and to molding pressure against its entire outer surface while upon the said mandrel, and withdrawing the said mandrel.

2. The process of making tubes that comprises impregnating a sheet of fibrous material with a phenolic condensation product as a binder, winding a dry sheet so treated about a mandrel without applying heat and pressure to build up a tubular body upon the mandrel, and first softening and then hardening the binder by applying heat and pressure against the entire outer surface of the tubular body so formed.

In testimony whereof I have hereunto subscribed my name this 11th day of Dec., 1914. 105

LOUIS T. FREDERICK.
